AUTOMOBILE WASHING UNIT

William E. Miller, Mill Valley, Calif.

Application March 15, 1954, Serial No. 29,524

Term of patent 14 years

(Cl. D49—1)

To all whom it may concern:

Be it known that I, William E. Miller, a citizen of the United States and a resident of Mill Valley, California, have invented a new, original, and ornamental Design for an Automobile Washing Unit, of which the following is a specification, reference being had to the accompanying drawing, forming a part hereof.

Fig. 1 is a front elevation of an automobile washing unit, showing my new design.

Fig. 2 is a side elevation.

Fig. 3 is a top plan view.

The lining on the two standards represents contrasting colored areas.

I claim:

The ornamental design for an automobile washing unit, as shown and described.
